Patented Mar. 28, 1916.

UNITED STATES PATENT OFFICE.

JOHN SCHUMACHER AND JOSEPH E. SCHUMACHER, OF LOS ANGELES, CALIFORNIA.

PLASTER-BOARD LATH.

1,177,361.

Specification of Letters Patent. Patented Mar. 28, 1916.

Application filed August 6, 1915. Serial No. 43,942.

To all whom it may concern:

Be it known that we, JOHN SCHUMACHER and JOSEPH E. SCHUMACHER, both citizens of the United States, residing at Los Angeles, in the county of Los Angeles and State of California, have invented new and useful Improvements in Plaster-Board Laths, of which the following is a specification.

This invention relates to an improved article of manufacture, specifically what is known as plaster-board lath, for use in building construction, in substitution for metallic or wooden lath, and to which plaster may be applied as it is applied to such latter forms of lath, to complete the wall surface. The lath is made, in accordance with the invention, of plaster-board consisting of a plastic composition of plaster and sawdust or other finely divided material, which ordinarily is incased between sheets of paper. This plaster-board is often employed to produce the final wall surface, by suitably decorating it. In accordance with the invention, we convert this plaster-board into lath by so forming it that the plaster applied to it to complete the wall surface is caused to effectively grip the plaster-board lath and be thereby anchored or held in position. This plaster-board lath is ordinarily formed in large sheets, which makes it possible to more quickly and inexpensively apply it than is the case when applying wood or metallic lath. It furthermore provides a continuous lath structure which is firmer and more weather-proof, and produces a more air-and-heat tight wall formation. Such large sheets of plaster-board lath are applied directly to the building frame or ceiling and wall beams by nailing or in any other suitable manner, and when the wall structure has been so completed, the plaster is applied over such plaster-board lath and becomes firmly anchored or attached thereto, due to the superficial formation of the plaster-board lath as will hereinafter be set forth. Furthermore, such plaster-board lath is fire-proof and is not subject to deterioration from rust or oxidation as is metallic lath. It may likewise be employed to produce the exterior wall structure, suitable weather-proof plaster being applied to it in such use.

With the above and other objects in view, including inexpensiveness in production and durability, the invention consists in the

novel and useful formation and construction of plaster-board lath hereinafter described, shown in the drawing and finally pointed out in claims.

In the drawing: Figure 1 is a face plan view of a sheet of plaster-board lath formed in accordance with the invention; Fig. 2 is a sectional view of the same, taken upon the line $\alpha^2-\alpha^2$, Fig. 1, looking in the direction of the appended arrows; Fig. 3 is an enlarged sectional view of a portion of the plaster-board lath in position as applied to the building structure, one of the beams or frame members of which is likewise shown in fragment, the plaster finish or surfacing being likewise shown as applied to the plaster-board lath; and, Fig. 4 is a view similar to Fig. 1, showing a modified form of plaster-board lath.

Corresponding parts in all the figures are designated by the same reference characters.

Referring with particularity to the drawing, and to Figs. 1 to 3 thereof, inclusive, the improved plaster-board is shown as comprising a body A of plastic material commingled with finely divided wood or other substances, interposed between, or to which are applied, surface sheets B of paper. This board is converted into lath by the production of a plurality of depressions, pits or key pockets b which are produced inwardly of such plaster-board from one surface thereof, by a suitable tool which compresses the material of the plaster-board and punches such pocket therein, shearing free a portion of the paper covering B at such surface of a size proportionate to the cross-section of the pocket, and punching the same inwardly of the pocket produced. At the same time, or as the punching tool is withdrawn, the following edge of the punch, which preferably is carried on a roller, lifts up a portion of the paper covering B adjacent to the formed pocket, producing a lip or anchor c, this being due to the fact that the action upon the following edge of the roller-carried punch tool upsets or mutilates the wall of the pocket at the rearward edge thereof, beneath such paper covering, and in being withdrawn from the pocket lifts up the portion of the paper covering as stated, to produce such lip. This is assuming that the roller, such as indicated at D in Fig. 2, in which d indicates the punches, moves upon its axis in contact with the plaster board sheet which is likewise moved in a

straight-away path beneath the roller. The punches are applied to the roller in straight series, and the punches of the several series may be in staggered relation throughout the 5 series. In the modified form shown in Fig. 4 in which a sheet of plaster-board lath is shown corresponding to that shown in Fig. 1, and provided with recesses or key pockets *e*, the paper covering *B* is elevated or 10 distorted to produce lips or anchors *f* at adjoining sides of the key pockets, due to the fact that the roller (not shown), which produces such pockets has its punches set in series which extend diagonally over the face 15 of the roller, or are in a sense slightly wound about the roller; the result being that as the plaster-board is passed beneath the rotating roller, two withdrawing faces of each punch mutilate the plaster-board body *A*, so as to 20 raise up and produce such two lips or anchors *f* as such withdrawing faces of the punches retreat from the plaster-board. As indicated more particularly in Fig. 3, the lips or anchors *e*, and this will be true of 25 the anchors *f*, are first projected more abruptly from the paper covering *B* in the formation of such lips or anchors, made necessary to accommodate the withdrawing punches. Afterward, such lips tend to bend 30 slightly inwardly or toward the plane of the plaster-board, as shown in full lines in Fig. 3. The first position of projection of such anchors is shown in dotted lines in Fig. 3. The final surface coating of plaster *E* is 35 applied over the plaster-board lath, as shown in Fig. 3, portions of the mass thereof entering the key pockets or recesses *b* and interlocking with the plaster-board lath, as clearly shown in Fig. 3 at *g*. In effect the 40 plaster becomes directly united with the plastic composition constituting the body *A* of the plaster-board lath, coming into intimate contact and intimate association therewith, at the four sides of each key pocket as 45 at *h*. Furthermore, the lips or anchors *e* protrude into and are embedded within the plaster mass or coating *E*, firmly interlocking therewith to produce a bonding effect, as is clearly indicated in Fig. 3. The mutilation 50 of the structure of the plaster-board body *A*, in the formation of the key pockets *b*, upon the withdrawal of the following edges of the punches, as at *h*, produces a more effective interlocking of such wall of 55 the key pocket with the key or tongue *g* of plaster *E*, which is anchored in the respective pocket. The paper and the plastic mass *E*, of course, adhere, assisting in the function 60 of holding the surface plaster to the plaster-board lath, but the tongues or keys *g* of the plaster more effectively and to a high degree of positiveness interlock the plaster coating with the plaster-board lath and intimately with the plastic body *A* thereof. 65 This, of course, is a much more positive as

sociation of the plaster and the plaster-board than would be possibly obtained by mere adhesion of the plaster to the paper covering *B*, for such adhesion would be no stronger in its holding effect than in the 70 strength of the paper itself. In effect, the plaster-board of the invention produces a positive and unfailing anchorage of the plaster covering directly to the body or substantial portion of the plaster-board, the 75 result being practically a unitary structure. It thus results that there is much less danger or liability of the plaster covering becoming cracked or split and tending to leave the 80 lath and fall. A wall or ceiling plaster surface is thus provided which is more sightly in appearance, is devoid of the danger incident to falling, and the attendant loss.

In Fig. 3 the plaster-board lath is shown 85 as applied to a structural member *G*, such as a ceiling or wall beam, by a nail or other securing device *l*.

It will be understood that the anchor *c* or the anchors *f* are bent outwardly from 90 the remaining covering or paper *B*, as the following edge of the punch rises from the formed pocket, such punch pressing upon the plastic body *A* beneath the paper, and so raising the paper and with it portions of 95 adhered plastic material which adds strength to such lip or anchor and reinforces the same to form it into an efficient bond or anchor.

It is manifest that many variations may 100 be made with respect to the particular form, shape and arrangement of parts, members and features in producing and forming plaster-board lath embodying the invention, all with respect to and in departure from 105 the showing of the accompanying drawing and the disclosure of the foregoing description, and likewise all without departing from the spirit of the invention and a fair interpretation thereof.

Having thus disclosed our invention, we 110 claim and desire to secure by Letters Patent:

1. Improved plaster-board lath having a 115 plurality of pockets therein adapted to receive intruding portions of plaster covering in interlocking engagement to hold the plaster covering to the lath; said lath having a plastic body and surface coverings of flexible material; a portion of such flexible material at one margin of each such pocket being angularly directed outwardly from the plastic body to constitute an anchor within the plaster covering.

2. Improved plaster-board lath having a 125 plurality of pockets therein adapted to receive intruding portions of plaster covering in interlocking engagement to hold the plaster covering to the lath; said lath having a plastic body and surface coverings of flexi- 130

- ble material; a portion of such flexible material at one margin of each such pocket being directed angularly outwardly from the plastic body to constitute an anchor within the plaster covering, and a portion of the wall of such pocket inward of such anchor being mutilated to present an uneven surface for direct engagement by such intruding plaster covering.
- 10 3. Improved plaster-board lath having a plurality of pockets therein adapted to receive intruding portions of plaster covering in interlocking engagement to hold the plaster covering to the lath; said lath having a plastic body and surface coverings of flexible material; a portion of such flexible material at one margin of each such pocket being directed angularly outwardly from the plastic body to constitute an anchor within the plaster covering, and a portion of the wall of such pocket inward of such anchor being mutilated to present an uneven surface for direct engagement by such intruding plaster covering; said anchor of said
- 15 flexible covering overhanging such mutilated pocket wall.
4. Improved plaster-board lath having a plurality of pockets therein adapted to receive intruding portions of plaster covering in interlocking engagement to hold the plaster covering to the lath; said lath having a plastic body and surface coverings of flexible material; a portion of such flexible material at one margin of each such pocket being directed outwardly from the plastic 30 body to constitute an anchor within the plaster covering; a portion of the plastic body being directed outwardly with such anchor to reinforce the same.
- 10 In testimony whereof, we have signed our 40 names to this specification in the presence of two subscribing witnesses.

JOHN SCHUMACHER.

JOSEPH E. SCHUMACHER.
